UNITED STATES PATENT OFFICE.

JULIUS MINTZ, OF NEW YORK, N. Y.

HAND-STAMP.

1,323,782.

Specification of Letters Patent.

Patented Dec. 2, 1919.

Application filed February 24, 1919. Serial No. 278,781.

To all whom it may concern:

Be it known that I, JULIUS MINTZ, a citizen of the United States of America, residing at New York city, Bronx county, State 5 of New York, have invented certain new and useful Improvements in Hand-Stamps, of which the following is a full, clear, and exact description.

This invention relates to improvements in 10 hand stamps, but more particularly to that class consisting of flexible bands carrying numeral or letter type, said bands being adjusted by hand when any combination of numerals or letters is needed.

15 One of the objections to this form of hand stamp is that it is quite impossible to adjust the bands without soiling the hands, as more or less ink will adhere to the bands. In this form of hand stamp the 20 numerals or letters selected are inked, just previous to use, by causing them to contact with an ink pad. The object of my invention is to provide a stamp of this nature, the bands of which can be adjusted without 25 soiling the hands. In the accompanying drawing.

Figure 1 is a face view of a hand stamp embodying my improvements;

Fig. 2 is a similar view, the bands being 30 omitted;

Fig. 3 is an enlarged vertical sectional view thereof;

Fig. 4 is an enlarged fragmentary detail view illustrating the mechanism for preventing movement of any one of the bands;

Fig. 5 is a face view of a modified form of my invention;

Fig. 6 is an end view illustrating the manner of attaching the handle plate thereto, 40 the bands being omitted, as well as other elements;

Fig. 7 is an enlarged fragmentary sectional plan view, the section being taken on line 7-7 in Fig. 5; and

45 Fig. 8 is a fragmentary detail view illustrating the connecting means for the handle plate and stamp frames.

While my improved stamp is arranged for manual manipulation, certain means are 50 provided to enable the operator to set the type carriers without soiling the hands or even touching the carriers. For this reason my improved stamp is much more cleanly than the usual form of hand stamps. In 55 the usual form of hand stamps, the carriers are adjusted independently of each other by

operating the drum which carries same. In my improved stamp the carriers are adjusted by means located exteriorly of the frame, certain means being provided to arrest the movement of the carriers not needed.

As herein arranged, my improved hand stamp consists of a frame 9 having a handle 10 and a drum 11 carried by a shaft 12 rotatably supported by the frame. At one end 60 of the shaft I place a knurled wheel 13 by which the drum 11 is rotated. The drum 11 carries all of the flexible type carriers, in this instance four, said carriers being indicated by 14, 15, 16 and 17. Each of the carriers is provided with a plurality of type, in this instance numerals, as illustrated in Fig. 1. When drum 11 is rotated, all of the carriers, 14, 15, 16 and 17 will move, there being a plate 18 provided at the lower 65 end of frame 9 for the carriers to move across and to provide a flat backing for the type. As the carriers will be adjusted one at a time to cause the desired numerals to be positioned at the lower end of the frame, 70 over plate 18, I provide special means to arrest the movement of all carriers excepting the one selected. To accomplish this result, 75 I provide a plate 19 carrying stops 20, one for each carrier, slidably mounted in slots 21 80 in said plate. As can be seen in Fig. 4, the plate 19 is disposed at an angle, relative to the carriers, in order that the shoes 22, which 85 form a part of the stops, can be moved into contact or away from the carriers. Each 90 stop 20 consists of the said shoes 22 carried by buttons 23 slidable in the slots 21. Normally, the stops will be out of contact with the carriers, hence the carriers can be moved. Should I desire to move carrier 14, for instance, to cause any particular type to register with plate 18, I would move the stops 20 opposite carriers 15, 16, 17 downwardly 95 to cause the shoes 22 thereon to contact with said carriers. When drum 11 is rotated, carrier 14 only will move. After having moved carrier 14, and should I desire to select a type on carrier 15, I would pull stop 20, opposite carrier 14 down, and stop 20 opposite carrier 15 up. When drum 11 is again 100 rotated, carrier 15 only will move. In the above manner, I am able to adjust each carrier, one at a time. While performing the above operations, the fingers will not come 105 in contact with the carriers and become 110 soiled.

Should I desire to provide stamps that can

be assembled into groups for the purpose of applying two or more lines of printing simultaneously, I provide rectangular frame-members 23 (Fig. 5) adapted to be placed end to end. To retain the frames in this formation, I provide a handle-plate 24 having flanges 25 to overlap the upper edges of the frame-member 23. The flanges 25 will be provided with studs 26 to enter openings 27 in the frame-members 23. This arrangement permits me to supply a handle-plate to retain a plurality of hand-stamp frames. As the drum which carries the type carriers is operable exteriorly of the frame, there is nothing to prevent said drums being smaller in diameter than the width of the frames; hence the frames can be abutted one against the other. In Fig. 5, the drums are indicated by 28 and the type carriers by 29, while 30 indicates the hand-wheels for rotating the drums. The stops for arresting the movement of the carriers 29 in the form of device shown in Fig. 5, are indicated by 31 and are carried by plates 32. In this form, the plates 32 will be set slightly within the frames, as indicated in Fig. 7.

In both forms of my devices the stops and manner of arresting the movement of the carriers will be the same. The type-carriers will be made preferably out of rubber-strips, and will be operated in the manner of a belt, or frictionally. Those carriers which are acted upon by the stops will not move when the drum is rotated.

35 Instead of adjusting the bands one at a time, I may operate all of them simultaneously and, by its stop, arrest the band, having the first number in the combination, as soon as said number reaches plate 18; the 40 band having the next number will then be stopped and so on, until all the numbers are selected. By this operation I avoid adjusting each band separately, and can accomplish the result by rotating drum 11 once.

45 After the desired number is selected, all the bands can be locked against displacement

by stops 20, to prevent irregularity of the type.

Having described my invention, what I claim is:—

50 1. In a hand-stamp, a frame, a plurality of flexible type-carriers movably supported by said frame, means to move the carriers simultaneously, and means to arrest the movement of any one of said carriers by 55 direct contact with the outer surface thereof.

2. In a hand-stamp, a frame, a plurality of flexible type-carriers movably supported by said frame, means to move said carriers simultaneously, and a stop mechanism for 60 each carrier to arrest the movement thereof at will by direct contact with the outer surface thereof.

3. In a hand-stamp, a plurality of flexible type-carriers, means common to all of said carriers to operate same, and means adjacent each carrier to arrest the movement thereof by direct contact with the outer surface 65 thereof.

4. In a hand-stamp, a frame, a rotatable 70 drum rotatably supported by the frame, a plurality of flexible type-carriers carried by said drum, a plate adjacent the carriers provided with slots, there being a slot opposite each carrier, and a stop for each carrier 75 slidably mounted in each slot.

5. In a hand-stamp, a frame, a rotatable drum rotatably supported by the frame, a plurality of flexible type-carriers carried by said drum, a plate adjacent the carriers disposed at an angle relative thereto, said plate being provided with a plurality of slots, there being a slot for each carrier, a stop 80 slidably mounted in each slot and consisting of a shoe to contact with its adjacent carrier, and a button to move said shoe.

Signed at New York city, N. Y., this 21 day of February, 1919.

JULIUS MINTZ.
